UNITED STATES PATENT OFFICE.

FRANK M. PETERS AND ALEXANDER DER ANANIAN, OF MILFORD, MASSACHUSETTS.

NAILING OR PEGGING MACHINE.

No. 878,891.

Specification of Letters Patent.

Patented Feb. 11, 1905.

Application filed February 14, 1907. Serial No. 357,335.

To all whom it may concern:

Be it known that we, FRANK M. PETERS and ALEXANDER DER ANANIAN, a citizen of the United States and a subject of the Sultan of Turkey, respectively, residing at Milford, in the county of Worcester and State of Massachusetts, have invented new and useful Improvements in Nailing or Pegging Machines, of which the following is a specification.

Our invention pertains to nailing or pegging machines; and it has for its general object to provide a machine designed more especially for nailing soles on shoe uppers, and embodying such a construction that it is possessed of large capacity, is reliable in operation, and requires but a minimum amount of attention from an operator incident to its operation.

20 The invention will be fully understood from the following description and claims when the same are read in connection with the accompanying drawings, forming part of this specification, in which:

25 Figure 1 is an elevation of one side of the machine constituting the present and preferred embodiment of our invention. Fig. 2 is a detail vertical section taken at a right angle to Fig. 1 and showing the nail-hopper 30 of the machine, and certain of the appurtenances thereof. Fig. 3 is a detail vertical section taken at a right angle to Fig. 1 and illustrating the mechanism for actuating the nail-feeder. Fig. 4 is a detail section showing 35 the means for controlling the gate of the nail-conduit. Fig. 5 is an elevation of the side of the machine opposite to that shown in Fig. 1. Fig. 6 is a plan view of the machine with the end portion of the member U at the left 40 broken away. Fig. 7 is a front elevation of the machine. Figs. 8 and 9 are vertical sections taken at right angles to each other and illustrating the head of the machine and the parts arranged therein, and also illustrating 45 modified springs; and, Figs. 10 and 11 are horizontal sections taken in the planes indicated by the lines 10 and 11, respectively, extending through Figs. 8 and 9.

50 Similar letters and numerals designate corresponding parts in all of the views of the drawings, referring to which:

A is a vertically-movable work-support designed to be raised by foot or other power in a manner that is well known in the art and 55 which I have deemed it unnecessary to illustrate. The said work-support is preferably

in the form of an arm, curved as shown to permit of the easy moving of a shoe on and around it; a portion of a shoe, which is lettered B, being shown in proper position on 60 the work-support in Fig. 1.

C is the main frame or body of the machine, which may be connected with and supported on a base (not shown), and is provided at its forward end with a vertically disposed tubular head D.

Fixed to and rising from the frame C at a point in rear of head D is an upright E, and on the said upright is fixed a nail-hopper F, best shown in Figs. 1, 2 and 6. The said nail-hopper is provided at one side with a vertically-disposed opening a, the side walls of which are preferably rabbeted, Fig. 6, and the bottom of the hopper is pitched or inclined downward in three directions 1, 2 and 3 to said opening a so as to assure nails placed in the hopper gravitating to the opening. Movable vertically through the said opening a of hopper F is a nail-feeder G which is also preferably rabbeted as illustrated, and is designed to be moved rectilinearly up and down by means presently described in detail.

The said nail-feeder G is arranged in the same vertical plane as the wall of the hopper F in which it moves, and its upper end b, which is of a width to support and raise one nail, is beveled as best shown in Fig. 2. At the outer side of that wall of the hopper F in which the nail-feeder G is arranged, is fixed a thin plate c of about the size and shape shown in Fig. 1, and at the outer side of said plate c is arranged an inclined nail-guide H, the walls of which are arranged sufficiently far apart to receive the shanks or bodies of the nails between them but not far enough to receive the heads of the nails. From this it follows that when the nail-feeder G is moved upward it will carry on its inclined end b one of the nails from the hopper F, and when said end b reaches the upper edge of the plate c the nail will drop laterally from the said end b of the feeder and over the upper edge of plate c and will assume an upright position in the guide H with its shank or body hanging between the walls of the guide and its head resting on the inclined upper edges of said walls.

It will also be apparent that because of the inclination of the upper edges of the guide-walls, the nails will move down the guide to the position shown by dotted lines in Fig. 1. On the wall of the guide H farthest from the hopper

If a guard flange *d* is provided, the office of which is to assure the nails assuming the position stated in the guide.

By reference to Fig. 1, it will be seen that the forward ends of the walls of the nail-guide *H* are recessed at *h* so that the upper portions of said ends extend forward beyond the lower portions thereof. This will be better understood by comparing Figs. 1 and

10 5. Connected to and depending from the nail-feeder *G* is a bar *e* through the medium of which the feeder is raised and lowered, and on the said bar *e* is an arm *f* which carries the nail cut-off *I* on which is a forward projection *g*. The cut-off *I* is of U-shape, as shown in Fig. 7; and it is designed when moved upward synchronously with the feeder *G*, to assume a position in the recess *h* of guide *H* and between the foremost nail and the following nail so as to prevent more than one nail passing to the nail-conduit *J* at a time. The upper portion of the said nail-conduit *J* is slotted and arranged immediately in front of the forward end of the space between the walls of guide *H* so as to enable the nails to pass while in an upright position from the guide to the conduit, and while still in an upright position to gravitate in the conduit. The foremost nail, however, is normally prevented from passing from guide *H* to conduit *J* by the arm of a spring *K* which is connected at *i* to the hopper *F*. Said arm of the spring *K* normally rests across the upper edges of the guide-walls in advance of the foremost nail, and it will be apparent that when the bar *e* is moved upward, the projection *g* on cut-off *I* will engage the arm of the spring *K* and by raising the same will release the foremost nail and permit the same to pass to the conduit *J*. But one nail, however, can pass from the guide *H* to the conduit *J* since when the cut-off *I* moves upward to raise the spring *K* and release the foremost nail, said cut-off will assume a position between the foremost nail and the following nail. On the subsequent downward movement of the cut-off, *I*, the arm of spring *K* will reassume its position on the guide *H* so that the mentioned following nail will 50 when released by the cut-off, assume a position against and be held by the said arm of spring *K*.

The nail-conduit *J* extends downward and forward from the discharge end of the guide *H*, and is provided at an intermediate point of its length with a horizontally-disposed slot *j*, Figs. 1, 3 and 4. This slot *j* receives a horizontally-swinging gate *L* for controlling the passage of nails through the conduit *J*. The said gate *L* is pivoted at one end *k* to a standard *l* on frame *C* so as to enable its other end to move into and out of the slot *j*; and the said gate is designed to be moved inward in the slot so as to catch and support a 65 nail, through the medium of a coiled spring

m, Fig. 4, contained in a fixed casing *n* and surrounding a pin *p* connected at *r* to gate *L*, and interposed between one end of the casing—i. e., the end toward the gate, and an abutment *s* on the pin. By virtue of this 70 arrangement it will be apparent that the spring *m* will tend to move the gate *L* toward the right in Fig. 4 with a view of closing the nail conduit *J*.

At the proper time in the operation of our machine, viz: when the bar *e* carrying the nail-feeder *G*, etc., is moved upward, the spring *m* is enabled to close the gate *L* so that said gate will catch and support the nail received in the conduit *J* from the nail-guide *H*. Then on the subsequent down movement of the said bar *e* and its appurtenances, a device in the form of an arm *M*, Figs. 1, 4 and 5, will press the pin *p* against the action of the spring *m* so as to open the gate and 80 enable the previously caught nail to pass to the lower end of the nail-conduit *J*—i. e., to the position shown in Fig. 8.

N is a horizontal rock-shaft journaled in suitable bearings at the opposite side of the frame *C*, with reference to the bar *e*. The said rock-shaft has fixed upon it the arm *M*, and it also has fixed upon it an arm *P*, which arm *P* is connected to and arranged to transmit motion to the bar *e*. The rock-shaft *N* is designed to be turned in the direction indicated by arrow by means hereinafter described, and it is returned to and normally held in the position shown by a pulling spring *Q*, Figs. 3, 5 and 6, which spring *Q* extends between and is connected to the frame *C* and an arm *R* fixed on the rock-shaft *N*. When the rock-shaft *N* is returned to the position illustrated, the vertically movable bar *e* and its appurtenances will assume the positions illustrated, and the gate *L* will assume the position shown in Figs. 1, 4 and 6. In addition to the arms *M*, *P* and *R*, the shaft *N* is equipped with an arm *S*, Figs. 1, 3, 5 and 7, through the medium of which it is 100 rocked in the direction indicated by arrow, as will be presently described.

T is an upright fixed to and rising from the frame *C*, at a point in rear of the head *D*, and *U* is a jaw-opener fixed, preferably in an adjustable manner on the upright *T*, and having a vertical opening *t* positioned above the head *D*; the side walls of the said opening *t* being beveled or inclined upward and inward, as shown in Figs. 1 and 7, for a purpose presently set forth.

The head *D* communicates at 4, Fig. 8, with the lower end of the nail-conduit *J*, and in the said head is arranged and adapted to move up and down a tube *V* in which is a vertical slot *5*, arranged when the tube *V* is moved upward to register with the opening 4 in the head and thereby permit a nail to pass from the lower end of the conduit *J* into the tube *V*. In its lower end the tube *V* is 125 130

provided with a central aperture 6 adapted to hold a nail precedent to the driving thereof; the upper end of the said aperture 6 being flared or funnel-shaped, as indicated by 7, to assure proper passage of the nails to the aperture. On the lower end of the tube V is a flange 8, and in the periphery of this flange is a notch 9 for the purpose of assisting in the operation of nailing a shoe in a regular line. 10 The flange 8 is also equipped with a guide 10 for the shoe; the said guide being held in place through the medium of a set screw 11 so that when not required for use the guide may be reversed and retained in an upwardly 15 extending position.

Attached to the upper portion of the tube V and movable with the same rectilinearly in the head D is a split tube W. This latter extends through an adjusting nut X on the 20 upper end of the head D, and is equipped at its upper end with a catch Y. Said catch comprises two lever members 12 pivoted to the split tube W and having their lower ends bifurcated and beveled, as best shown in 25 Figs. 1, 5 and 9, and a coiled spring 13 interposed between the upper arms of the lever members and having for its office to press said upper arms apart with a view of yieldingly pressing the lower arms inward or toward each other. When the tube V and the 30 split tube W are moved upward by the raising of the work-support A, the upper arms of the lever members 12 comprised in the catch Y are designed to take into or move upward 35 in the opening t of the jaw-opener U, when the opposite inclined walls of said opening t will move the upper arms of the lever members inward against the action of the spring 13, and the lower arms or jaws of the lever members outward, the latter to release the head Z on the nail-driving hammer A'. The 40 said nail-driving hammer A' is movable rectilinearly in and independent of the tubes V and W, and its lower end 20 is reduced as 45 shown so as to enable it to follow a nail through the aperture 6 in the lower end of the tube V. The depth to which the heads of the nails are driven into the shoe sole is governed by the adjusting nut X between 50 which and the hammer-head Z a washer B' is preferably interposed as shown. When the 55 said nut X is turned in one direction it obviously serves to raise the hammer A', while when it is turned in the opposite direction it lowers the hammer. At its upper end the split tube W carries a cross-rod C', the office of which is to engage a plate 21, Fig. 3, arranged on a vertically movable rod 22 and backed by a spring 23 with a view of raising 60 the said rod 22. Said cross-rod C' also serves to fix the head Z on the hammer A'. The plate 21 is loose on the rod 22 and the spring 23 is provided above said plate with a view of cushioning the blow of the cross-rod C' 65 there against.

The rod 22 is loosely connected at its lower end to one arm of a vertically swinging lever 24, which lever is fulcrumed at 25 and has its other arm connected through a link 26 with the arm S on the before described rock-shaft N, whereby it will be apparent that when the tubes V and W are moved upward, the shaft N will be rocked in the direction indicated by arrow to move the bar e and its appurtenances upward to assure the supply of a nail to the conduit J, and to throw the arm M outward to assure the catching of said nail on the gate L. At this point it is well to state that the catching of the nail on the gate L in the manner described incident to upward movement of the tubes V and W is advantageous for the reason that when the slot 5 in the tube V registers with the lower end of the nail-conduit J but one nail can pass into the tube V—i. e., the nail released from the gate L on the previous movement of the rock shaft N in the direction opposite to that indicated by arrow.

The tubes V and W are pressed upward by the work-support A, and they may be moved downward either by the exterior springs D' interposed between and connected to the cross-rod C' and the head D, as shown in Figs. 1, 5, 6 and 7, or by the internal spring D² contained in the head D and interposed between a washer 30 on tube V and the nut X, as shown in Figs. 8 to 11. The hammer A' is moved upward by the tubes V and W through the engagement between the catch Y and the hammer head Z, and when its said head Z is released from the catch Y in the automatic manner before described, it may be forcibly impelled downward either by the exterior springs E' interposed between and connected to the head D and a rod F' carried by the head Z, as shown in Figs. 1, 5, 6 and 7, or by the internal spring E² shown in Figs. 8 to 11. The said spring E² is coiled about the hammer A' and is connected to the head D by a pin 40 and to the hammer A' at 41. By virtue of this arrangement the spring E² will be stretched or expanded when the hammer is raised, and consequently will operate immediately subsequent to the release of the hammer head Z from the catch Y to forcibly 115 impel the hammer downward.

The general operation of our novel machine is as follows: When the work-support A and the shoe B thereon are moved upward, the tubes V and W will also be moved upward together with the hammer A', the latter because of the hammer-head Z being engaged by the catch Y. Synchronously with the described upward movement of the tubes V and W and the hammer A', the shaft N is rocked in the direction indicated by arrow through the connections described, to raise the nail-feeder G, the nail cut-off I, and the nail retainer or spring K so as to effect the transfer of one nail from the guide H to the 120 125 130 135 140 145 150 155 160 165 170 175 180 185 190 195 200

conduit J, and to assure the gate L being closed to catch the said nail. As the tube V moves upward and the slot 5 therein registers with the lower end of the conduit J, the nail 5 released by the gate L on the previous downward movement of the tubes V and W will pass from the lower end of the conduit J into the tube B and assume a position in the central aperture 6 of the tube with its lower end 10 resting on the sole of the shoe. During the completion of the upward movement of the tubes V and W, the jaw-opener or catch releaser U will engage the catch Y and automatically open the jaws of the same so as to 15 release from said jaws the hammer head Z, when the external springs or the internal spring before described as complementary to the hammer will forcibly impel the hammer downward and cause said hammer to 20 properly drive the previously positioned nail into the shoe. On the subsequent downward movement of the work-support A and the shoe B, the external springs or the internal spring complementary to the tubes V 25 and W cause downward movement of the tubes to the position illustrated, at the same time causing the gate L to release the tack, when the operation described is repeated until the nailing of the shoe or other work is 30 completed.

It will be gathered from the foregoing that our novel machine is designed more especially for use by shoe-makers or cobblers; and it will also be gathered that any means suitable 35 to the purpose of the invention may be employed to raise the tubes V and W. For this latter reason we do not desire to be understood as confining ourselves to the employment of a work-support for effecting 40 the purpose stated, though we prefer to employ a work-support such as shown or any other suitable work-support. We would also have it understood that without involving departure from the scope of our invention 45 as defined in the appended claims, a nail-feeding means other than that described may be employed in connection with the head D and its appurtenances. In this connection, however, we desire it distinctly understood 50 that the nail-feeding means shown and described is preferable because it is automatic and reliable in operation, and at the same time well adapted to withstand the usage to which such mechanism is ordinarily 55 subjected. We would further have it understood that the nail-feeding mechanism described may be used in connection with any nail-holding and driving mechanism other than that described without involving departure from the scope of our claimed invention, though for obvious reasons we prefer to 60 employ the latter nail-holding and driving mechanism.

The specific construction herein shown and 65 described constitutes the preferred embodiment

of our invention, as stated, but it is obvious that in practice various changes in the form, construction and relative arrangement of parts may be made without involving departure from the scope of our claims. 70

Having described our invention, what we claim and desire to secure by Letters Patent is:

1. The combination in a nailing machine, of movable means arranged to receive and hold nails, nail-driving means movable independent of the nail receiving and holding means, means on the nail receiving and holding means for engaging the nail-driving means and moving the same with the nail receiving and holding means, and means for automatically releasing the said nail-driving means from said nail receiving and holding means. 75 80

2. The combination in a nailing machine, of movable nail-holding means, nail-driving means movable independent of the nail-holding means, means on the nail-holding means for engaging the nail-driving means and moving the same with the nail-holding means, means for automatically releasing the said nail-driving means from said nail-holding means, and nail-feeding means operated by said nail-holding means. 85 90

3. The combination in a nailing machine, of a frame, a movable nail-holder, a hammer movable independent of the nail-holder, means on the nail-holder for engaging the hammer and moving the same with the holder, means on the frame for automatically releasing the said hammer from said means on the holder, and a spring for forcibly impelling the hammer subsequent to its release. 95 100

4. The combination in a nailing machine, of a frame, a movable tube for receiving and holding nails, a hammer movable in and independent of the tube, means on the tube for engaging the hammer and moving the same with the tube, means on the frame for automatically releasing the hammer from said means on the tube, and a spring for forcibly impelling the hammer subsequent to its release. 105 110

5. The combination in a nailing machine, of a frame, a tube movable rectilinearly in said frame and arranged to receive and hold nails, a spring for moving said tube in one direction, a hammer movable rectilinearly in the tube and having a head, a spring for moving the hammer forcibly in one direction, a catch carried by the tube and arranged to engage the hammer head and move the hammer with the tube so as to place the hammer spring under tension, and means on the frame for disengaging the catch from the hammer head. 115 120 125

6. The combination in a nailing machine, of a frame having a tubular head, a catch releaser positioned above the head and hav- 130

ing an opening, opposite walls of which are inclined upward and inward, a tube movable rectilinearly upward and downward in said head and arranged to receive and hold nails, 5 a spring for moving said tube downward, a hammer movable up and down in the tube and having a head, a spring for impelling the hammer downward, and a catch carried by the tube and having spring-pressed jaws 10 for engaging the hammer head and also having arms on said jaws arranged to be engaged and moved inward by the opposite inclined walls of the catch releaser.

7. The combination in a nailing machine, 15 of a frame having a tubular head in which is an opening, a tube or conduit communicating with and arranged to conduct nails to said opening, a tube movable rectilinearly upward and downward in said head and having 20 an opening arranged to be registered with the opening in the head for the passage of nails from the conduit into the tube, a catch releaser positioned above the head, a spring for moving said tube downward, a hammer movable up and down in the tube, a spring 25 for impelling the hammer downward, and a catch carried by the tube and arranged to engage and raise the hammer and also arranged to be engaged by the catch releaser 30 and disengaged from the hammer.

8. The combination in a nailing machine, 35 of a frame having a tubular head in which is an opening, a conduit extending to the opening in the tubular head, a gate controlling the passage of the conduit, a spring for closing said gate, a rock-shaft provided with means for opening the gate of the conduit, a tube movable rectilinearly upward and downward in the head of the frame and having 40 an opening arranged to be registered with the opening in the head for the passage of nails from the conduit into the tube, a catch releaser positioned above the head, a spring for moving said tube downward, a hammer movable up and down in the tube, a spring 45 for impelling the hammer downward, a catch carried by the tube and arranged to engage and raise the hammer and also arranged to be engaged by the catch releaser and disengaged 50 from the hammer, means intermediate the tube and the rock-shaft for operating the latter by the former and means operated by the rock-shaft for feeding nails to the conduit.

55 9. The combination in a nailing machine, of a frame having a tubular head in which is an opening, a conduit extending to the opening in the tubular head, a gate controlling the passage of the conduit, a spring for closing said gate, a rock-shaft having an arm 60 arranged to open the conduit gate, a tube movable rectilinearly upward and downward in the head of the frame and having an opening arranged to be registered with the

opening in the head for the passage of nails 65 from the conduit into the tube and also having a cross-rod, a catch releaser positioned above the head, a spring for moving said tube downward, a hammer movable up and down in the tube, a spring for impelling the hammer downward, a catch carried by the tube and arranged to engage and raise the hammer and also arranged to be engaged by the catch releaser and disengaged from the hammer, a lever fulcrumed at an intermediate 70 point of its length and arranged to swing vertically, a link connecting one arm of said lever and an arm on the rock-shaft, a vertically movable rod connected to the other arm of the lever and having a portion arranged to be engaged and moved upward by the cross-rod on the tube, and means operated by the rock-shaft for feeding nails to the conduit.

10. The combination in a nailing machine, 85 of a frame, a movable nail-holder, a hammer movable independent of the nail-holder, means on the nail-holder for engaging the hammer and moving the same with the holder, means on the frame for automatically 90 releasing the said hammer from said means on the holder, a spring for forcibly impelling the hammer subsequent to its release, and nail-feeding means operated by said holder.

11. The combination in a nailing machine, 95 of a frame, a tube movable rectilinearly in said frame and arranged to receive and hold nails, a spring for moving said tube in one direction, a hammer movable rectilinearly in the tube and having a head, a spring for 100 moving the hammer forcibly in one direction, a catch carried by the tube and arranged to engage the hammer head and move the hammer with the tube so as to place the hammer spring under tension, 105 means on the frame for disengaging the catch from the hammer head, and nail-feeding means operated by the tube.

12. The combination in a nailing machine, 110 of movable means arranged to receive and hold nails, nail-driving means arranged in and movable independent of the nail receiving and holding means, means on the nail receiving and holding means for engaging the nail-driving means and moving the same 115 with the nail receiving and holding means, and means for automatically releasing the said nail-driving means from said nail receiving and holding means.

In testimony whereof we have hereunto 120 set our hands in presence of two subscribing witnesses.

FRANK M. PETERS.
ALEXANDER DER ANANIAN.
